UNITED STATES PATENT OFFICE.

JOHN H. SCHUSSLER, OF CHICAGO, ILLINOIS.

INKING-ROLLER FOR PRINTING-PRESSES.

1,310,932.

Specification of Letters Patent. Patented July 22, 1919.

Application filed October 19, 1917. Serial No. 197,389.

To all whom it may concern:

Be it known that I, JOHN H. SCHUSSLER, a citizen of the United States, and resident of Chicago, in the county of Cook and State 5 of Illinois, have invented certain new and useful Improvements in Inking-Rollers for Printing-Presses, of which the following is a specification.

My invention relates to improvements in 10 inking rollers for printing presses of the same kind as those described in my co-pending application Serial No. 185,888, filed August 13, 1917, and has for its particular object the provision of adjustable bearings 15 whereby the inking rollers can always be secured in close contact with the printing surface and inking disk.

A further object of my invention is to 20 provide ball bearings for inking rollers, thus serving to lessen the friction, and also to secure the rotation of the inking rollers with a less amount of power than would be required in an ordinary bearing.

A further object of my invention is to 25 provide a simple built-up bearing which may be readily assembled or taken apart so as to replace any worn or defective part.

A still further object is the provision of a 30 bearing which may be adjusted in such manner that the inking rollers will contact with the printing surface only as the rollers travel over the printing surface in one direction if it is so desired.

My invention will be further and better 35 understood by reference to the accompanying drawings, in which—

Figure 1 is an elevation showing the ends of the bearings carried by oppositely disposed hook members;

Fig. 2 is a sectional view through one of the bearings and one of the frictional rollers;

Fig. 3 is a sectional view on line 3—3 of Fig. 2;

Fig. 4 is a sectional view on line 4—4 of Fig. 2.

Fig. 5 is a plan view of the oppositely disposed hook members; and,

Fig. 6 is a view showing the device for limiting the rotation of the eccentric bearings.

Referring now specifically to the drawings, in which like reference characters indicate like parts throughout, 10 is the traveling or reciprocatory member carrying a

head 10^a at its outward end, the said head 55 member having oppositely disposed hooks 11 and 12, within which are mounted the bearings carrying the inking rollers. Frictional rollers 13 and 14 are mounted within the bearings, the peripheral surfaces of these 60 rollers engaging in frictional contact with a track 15 on the frame 15^a and transmitting motion to the inking roller 16, (Fig. 2), thus insuring the rotation of the inking roller as the traveling member 10 moves upward and 65 downward. The inking roller has a reduced or shaft portion 17, over the end of which is mounted an eccentric cylindrical cap member 18 having a squared end 19 in order that a wrench may be fitted thereon so that the 70 eccentric member can be turned to any desired position. The eccentric member 18 is fitted into the hooked portions 11 and 12 of the head 10^a, and is secured in said hooked portions by means of a nut 20 having 75 threaded engagement with the outside end of said eccentric, and which when screwed up tightly holds the bearing in position, the inside of the hook abutting against a collar 21 which is fitted over the eccentric and 80 which in turn abuts against an annular shoulder 21^a on the eccentric 18. Mounted on the inner end of the cylindrical eccentric 85 is a built-up frictional roller 13, the said frictional roller having an outside portion 22 composed of rubber or other resilient material so as to insure a gripping surface for the roller as it travels up and down on the track 15. The built-up frictional roller is composed of a member 23 having an opening 90 therein to fit over the cylindrical eccentric 18, and which fits snugly against an annular shoulder 24 formed upon the cylindrical eccentric 18. Forming a part of said frictional roller 13 is a ring or annular portion 25 which forms a seat for the resilient portion 22 and also forms a bearing surface for the ball bearings 26 interposed between said member 25 and the eccentric member 18, and which has a vertical portion 27 95 formed integral therewith, which vertical portion affords means for holding one row of the ball bearings 26 in position. The member 23 has a shoulder 28 formed thereon upon which the outside edge of the member 25 rests, the member 23 also abutting against the annular shoulder 24 formed on the eccentric 18. The shoulder portion 28 of the

member 23 forms a vertical bearing and retaining means for another row of ball bearings 30.

A washer 31 is inserted between the rows 5 of ball bearings 26 and 30 and serves to hold each of these rows of ball bearings apart and also an inside bearing surface. Forming the inside portion of the frictional roller 13 is a member 32 which is connected with the member 23 by means of bolts 33 which pass through the portion 22, said bolts having their heads countersunk in the member 23 and having threaded engagement with the member 32. Fitted to the shaft portion 17 10 of the inking roller 16 is an annular member 34, the said member 34 having grooves 35 extending transversely across its inside face. Pins 36, 36 are inserted into the vertical portion 27 of the member 25 and protrude into 15 the transverse grooves 35 in the member 34, so that as the frictional roller revolves, motion is transmitted to the member 34 and thence to the inking roll. Or if it is desired, lugs may be formed on the member 25 so 20 as to fit into the outside portion of the transverse groove 35 in the member 34. A key 37 is attached to the shaft portion 17 of the inking roller 16, and fits into a recess 38 of the member 34. The outside diameter 25 of the member 34 is less than the inside diameter of the member 25, and therefore fits loosely within said member 25. The member 30 has shoulder portions 39, 39 formed integral therewith, the said shoulders 39 being 30 exactly opposite each other, thus making one-half of the member 21 approximately double the width of the other half of the said member, the wider portions of the member 21 being cut transversely so as to 35 form shoulders 39, 39. Attached to the hooks 11 and 12 are clamps 40, 40, the said clamps being held in position by means of lug screws 41, 41, screwed tightly against the surface of the hook members 11 and 12. 40 Through the thick portion of the eccentric 45 18 a hole 42 is drilled, a corresponding hole 42 being drilled through the member 21 and a pin inserted through the member 21, the member 21 being thereby keyed to the eccentric 50 so as to prevent rotation upon said eccentric member 18.

In adjusting the inking roller 16, the nut 20 is loosened and a wrench applied to the square portion 19 of the eccentric 18, when 55 said eccentric can be turned to any desired position, and the printing roller 16 secured to any desired adjustment with relation to the printing surface or inking disk. The nut 20 will thereupon be tightened and the 60 clips 40, 40 adjusted to such position on the hooks 11 and 12 that one pair of the shoulders 39, 39 of the members 21, 21 will abut against the said clips. It will be understood, of course, that the inking rollers are 65 reciprocated by means of a pair of travel-

ing members, only one of which, the member 10, is shown, and are rotated through the friction rollers 13 and 14 coming in contact with the track on the frame of the press, the friction roller 23 turning upon the ball bearings mounted upon the eccentric portion and in turn transmitting its motion to the member 34 through the pins 36, 36 fitted into the groove portion of the member 34, which is keyed to the shaft portion 17 of the inking roller 16. Therefore, the reciprocation of the arms 10 and the contact of the frictional rollers 13 and 14 rotate the inking rollers 16, thus securing an even distribution of ink upon the inking roller and 80 also upon the printing surface.

If it is desired, the nuts 20 may not be screwed tightly against the hook members 11, when the eccentric portion 18 will reverse itself at the extreme points of its path 85 of movement, and the eccentric member 18 will make approximately a one-half revolution, carrying with it the member 21 around to the point where one of the pair of shoulders 39 will contact with the clip 40, and the printing roller 16 will thereby be thrown out of contact with the printing surface in one direction of its movement as it passes over the printing surfaces. The clips 40, 40 may be positioned on the hooks 90 11 and 12 at any desired place, thus insuring proper adjustment of the inking roller with relation to the printing surface at all times.

It is apparent that many modifications 100 may be made of the arrangement which I have shown, but all of such modifications or changes which are within the scope of my invention I consider to be embodied in the improvements herein shown and claimed. 105

I claim:

1. In a printing press a combination of an inking roller, traveling supports upon which said inking roller is mounted, a rotatable eccentric journal bearing carrying 110 said inking roller, means for limiting the rotation of said journal bearing, a frictional roller mounted upon said eccentric member, and means mounted upon the inking roller for engagement with the frictional roller. 115

2. In a printing press, the combination of inking rollers, traveling supports upon which said inking rollers are mounted, rotatable eccentric journal bearings carrying the shafts of said inking rollers, means for limiting the rotation of said journal bearings, frictional rollers mounted upon said eccentric members, and members carried by the shafts of the printing rollers and in engagement with the frictional rollers. 120

3. In a printing press a combination of an inking roller, traveling supports upon which said inking roller is mounted, a rotatable eccentric journal bearing connecting said traveling supports and the shaft of the 125 130

5 said inking roller, adjustable means for limiting the rotation of the said journal bearing, and a frictional roller mounted upon said eccentric member and connected to said 10 inking roller.

10 4. In a printing press, the combination of inking rollers, traveling members carrying said inking rollers, rotatable bearings connecting the shafts of said inking rollers with 15 the traveling members, adjustable means for limiting the rotation of said bearings and frictional rollers mounted upon said rotatable bearings and connected to the shafts of said inking rollers.

15 5. In a printing press, the combination of inking rollers, traveling members carrying said inking rollers, rotatable eccentric members secured to the shaft portions of said inking rollers, friction rollers contacting 20 with the frame of the printing press and mounted upon said eccentric members, adjustable means for limiting the rotative movement of the eccentric members and means connecting said friction rollers with 25 the shafts of said inking rollers.

30 6. In a printing press, the combination of inking rollers, traveling members carrying said inking rollers, rotatable eccentric members carrying the shaft portions of said inking rollers and frictional rollers mounted upon said eccentric members and contacting with the frame of said printing press, means 35 for limiting the rotative movement of said eccentric members and means connecting said frictional rollers and said inking rollers whereby the said inking rollers are actuated.

40 7. In a printing press, the combination of inking rollers, traveling members carrying said inking rollers, rotatable eccentric members carrying the shaft portions of said inking rollers, locking means for securing said eccentric members in any predetermined position, and frictional rollers mounted upon said eccentric members and contacting with 45 the frame of the printing press whereby the said inking rollers are actuated.

50 8. In a printing press, the combination of inking rollers, traveling members carrying said inking rollers, rotatable eccentric members mounted upon said traveling members and carrying the shaft portions of said inking rollers, means for limiting the rotative movement of said eccentric members, frictional rollers mounted upon said eccentric 55 members and contacting with the frame of said printing press, and connections between said frictional rollers and said inking rollers whereby the inking rollers are actuated.

60 9. In a printing press, the combination of inking rollers, traveling members with heads attached thereto, said heads having oppositely disposed hook portions, eccentric members carried within said hook portions and within which the shafts of said inking 65 rollers are carried, frictional rollers mounted

upon said eccentric members and contacting with the frame of the printing press, connections between the shafts of said inking rollers and said frictional rollers, and means whereby the rotatable movement of said eccentric members is limited. 70

10 10. In a printing press, the combination of inking rollers, traveling members with heads attached thereto, said heads having oppositely disposed hook portions, eccentric members 75 carried within said hook portions and within which the shafts of said inking rollers are carried, frictional rollers mounted upon said eccentric members and contacting with the frame of the printing press, connections between the shafts of said inking rollers and said frictional rollers, and clips carried by said hooks whereby the rotatable movement of the said eccentric members is limited. 80

11 11. In a printing press, the combination of inking rollers, traveling members with heads attached thereto, said heads having oppositely disposed hook portions, rotatable eccentric members carried within said hook portions and within which the shafts of said 85 inking rollers are carried, frictional rollers mounted upon said eccentric members and contacting with the frame of the printing press, connections between the shafts of said inking rollers and said frictional rollers, and adjustable clips carried by said hooks whereby the rotatable movement of said eccentric members is limited. 90

12 12. In a printing press, the combination of inking rollers, traveling members with heads attached thereto, said heads having oppositely disposed hook portions, rotatable eccentric members carried within said hook portions and within which the shafts of said inking rollers are mounted, frictional 100 rollers mounted upon said eccentric members and contacting with the frame of the printing press, annular members mounted upon the shafts of said inking rollers, means carried by said frictional rollers for engagement 105 with the said annular members and adjustable clips carried by said hooks whereby the rotatable movement of the said eccentric members is limited. 110

13 13. In a printing press, the combination of inking rollers, traveling members with heads attached thereto, said heads having oppositely disposed hook portions, rotatable eccentric members carried within said hook portions and within which the shafts of said 115 inking rollers are mounted, frictional rollers mounted upon said eccentric members and contacting with the frame of the printing press, annular members mounted upon the shafts of said inking rollers, pins carried by 120 said frictional rollers for engagement with the said annular members, and adjustable clips carried by said hooks whereby the rotatable movement of the said eccentric members is limited. 125

14. In a printing press, the combination of inking rollers, traveling members with heads attached thereto, said heads having oppositely disposed hook portions, rotatable eccentric members carried within said hook portions and within which the shafts of said inking rollers are mounted, frictional rollers mounted upon said eccentric members and contacting with the frame of the printing press, annular members mounted upon the shafts of said inking rollers and within said traveling members having a transversely extending groove across one of its faces, pins secured to said frictional rollers and projecting into the said transversely extending groove for engagement with the said annular member, and adjustable clips carried by said hooks whereby the said rotatable movement of the said eccentric members is limited.
15. In a printing press, the combination of inking rollers, traveling members with heads attached thereto, said heads having oppo-

sitely disposed hook portions, rotatable eccentric members carried within said hook portions and within which the shafts of said inking rollers are mounted, frictional rollers mounted upon said eccentric members and contacting with the frame of the printing press, annular members mounted upon the shafts of said inking rollers and within said frictional rollers and having a less outside diameter than the portion of the frictional roller within which it is mounted, and having a transversely extending groove, means carried by said frictional rollers and extending into the said transversely extending groove for engagement with said annular member, and adjustable clips carried by said hooks whereby the rotatable movement of the said eccentric members is limited. 40

In witness whereof, I hereunto subscribe my name this 29th day of September, A. D. 1917.

JOHN H. SCHUSSLER.
